UNITED STATES PATENT OFFICE.

MORRIS P. BRAY, OF WORCESTER, ASSIGNOR TO THEODORE C. BATES, OF NORTH BROOKFIELD, MASSACHUSETTS.

DESIGN FOR A CORSET.

SPECIFICATION forming part of Design No. 12,937, dated March 28, 1882.

Application filed January 23, 1882. Term of patent 7 years.

To all whom it may concern:

Be it known that I, MORRIS P. BRAY, of Worcester, in the county of Worcester and State of Massachusetts, and a citizen of the United States, have invented and produced a new and original Design for the Breast-Covering Portion of Corsets, of which the following is a specification, reference being had to the accompanying drawings, forming part thereof.

Figure 1 represents in front elevation sufficient of the breast-covering portion of the front of a corset to illustrate my design; and Figs. 2 and 3, other drawings, showing portions of corsets with the top piece of Fig. 1, the downwardly-extended points of which constitute my design divided, Fig. 2 showing the two side points, and Fig. 3 only the center point.

The breast-covering portion entering into my design is composed of the gores *a* *b* and centerpiece, *c*. The gores and centerpiece are surmounted by a top piece, *d*, extended entirely across them, and with its upper edge even with the side pieces, *e* *f*, of the corset. The lower edge of the top piece is provided

with a series of scallops or inward corners to 25 form points 2 3 4. Points 3 and 4 extend down over and cover the upper portion of the gores *a* *b*, and the point 2, preferably longer than points 3 or 4, extends down over and upon the upper end of the center piece, *c*, thus making 30 a very neat appearing and tasteful front to cover the breast.

I might omit the center point, 2, or, again, I might omit both points 3 4, and yet not depart from my design.

The leading feature of my design is the scallops or points extended over the pieces entering into the formation of the breast-covering portions.

I claim—

The herein-described design for corset-front.

In testimony whereof I have signed my name to this specification in the presence of two subscribing witnesses.

MORRIS P. BRAY.
